UNITED STATES PATENT OFFICE.

HERBERT E. VAN DORN, OF CHICAGO, ILLINOIS.

TRAIN-LINE COUPLER.

Application filed May 9, 1921. Serial No. 468,059.

My invention has for its object to produce a simple, novel, compact and efficient device for connecting together the electrical circuits on two adjacent railway cars.

The various features of novelty whereby my invention is characterized will herein-after be pointed out with particularity in the claims; but, for a full understanding of my invention and of its object and advantages, reference may be had to the following detailed description taken in connection with the accompanying drawings, wherein:

Figure 1 is a top plan view of a fragment of a car coupler having one of my improved electrical couplers attached thereto;

Fig. 2 is a vertical transverse section through the electrical coupler detached from the car coupler and lying flat on its side;

Fig. 3 is a section taken approximately on line 3—3 of Fig. 2;

Fig. 4 is a side elevation of the electrical coupler, a part of the cover being removed and the casing being shown partly in section, the view being taken looking down on Fig. 2; and

Fig. 5 is an end view of the electrical coupler occupying the same position as in Fig. 2.

Referring to the drawing, 1 represents a flat casing, preferably rectangular in cross section, open at the front end and having at the rear end a sleeve or nipple, 2, for the insertion of wires or a cable. One side of the casing is also preferably open as indicated at 3, to permit ready inspection of the connections; the open side being closed by means of a plate secured in position by means of screws, 5, or otherwise. At the side of the casing opposite the side 3 are projecting ears, 6 and 7, by means of which the casing may be attached to a suitable support.

Within the casing is a body of insulating material of a size and shape to fill the front half of the casing and adapted to be placed into the casing and removed therefrom through the open front end, this body of insulating material carrying contacts adapted to project out beyond the front end of the casing for engagement with similar contacts on the co-operating coupler. In the arrangement shown, there are six contacts in the form of bars, the front end of each bar being made rectangular in cross

section as indicated at 8, and the remainder of the bar being in the form of a cylindrical stem or shaft, 9, smaller in diameter than the long sides of the rectangular portion, so that each bar has a rearwardly-facing shoulder at the front end of the shaft or stem. The body of insulating material is made up out of a series of blocks engaging each other along planes containing the longitudinal axes of the contacts, the number of blocks being preferably one greater than the number of contacts. Each intermediate block, 10, is recessed on its upper and lower faces, that is the faces which engage with the adjacent blocks, the upper block, 11, is recessed on its under face, and the lowermost block, 12, is recessed on its upper face, in such a manner as to provide one-half of a complete seat for one of the contact bars, including a chamber for a spring. In the arrangement shown, each of these recesses comprises a part, 13, at the front, for receiving the rectangular portion of a contact bar, a semi-cylindrical part, 14, at the rear for receiving the cylindrical stem or shaft of the bar, and an intermediate part, 15, which may conveniently extend across the entire width of the block and serve as a chamber for a coiled spring, 16, surrounding the front end of the stem or shaft and engaging with the rearwardly-facing shoulder, 17, at the rear end of the rectangular portion of the bar. The several insulating blocks are preferably tied together in some manner to form a single unit which may be placed in the casing or taken out of the latter without disturbing the adjustments of the contacts relatively to the blocks. To this end I have inserted through the blocks one or more tubes, 18, into the ends of which screws, 19, are inserted, the heads of the screws engaging the outer faces of the upper and lower blocks and serving to draw the entire group of blocks closely together. In the arrangement shown, there are two of these tubes, one at each of two diagonally-opposed corners. It will thus be seen that the several blocks may be fastened together before the contact bars are placed in position, the springs being afterwards inserted laterally into the chambers 15 and the contact bars being then inserted into the seats or recesses from the front. After the contact bars have been placed in position suitable nuts, 20, are screwed upon the rear end, these nuts bearing

ing against the rear ends of the blocks and preventing the withdrawal of the bars. The stems or shafts of the contact bars are made long enough to permit other nuts, 21, to be placed upon the extreme rear ends for the purpose of fastening the leading-in wires, not shown, to the bars.

If desired, the front ends of the blocks may be flanged laterally, as indicated at 22, 10 22, these flanges engaging with the front edges of the two side walls of the casing and limiting the inward movement of the insulating body into the casing. After the coupling unit has been placed in the casing a 15 pair of bolts, 23, 23, are inserted through the same and through the top and bottom walls of the casing parallel with the tubes 18 and in the vicinity of the two corners not occupied by these tubes. In order to hold 20 the coupling unit firmly in position and avoid any looseness between the same and the casing I provide the top wall of the casing with a pair of set screws, 24, 24, which bear down against the top of the uppermost 25 block of insulating material and thus press the entire body of insulating material firmly against the bottom wall of the casing.

Encircling the front end of the casing is a band, 25, preferably of rubber, which projects somewhat beyond the front edge of the casing, although not as far as the front ends of the contact bars. The result is that when two couplers come together the contact bars mutually press each other inwardly and 30 then the rubber strips on the ends of the casings come in contact with each other and are compressed more or less so as in effect to seal the joint between the two couplers.

My improved electric coupler may of 40 course be mounted on a car in any suitable way, but I prefer to mount it on a car coupler so as to make it possible simultaneously to effect the coupling of the cars and of the circuits thereon. I furthermore prefer to 45 mount the electrical coupler on a car coupler of a type which will produce more or less of a relative lateral movement between two co-operating couplers just before the car couplers reach their final coupled position. 50 By this means, after the contacts on two co-operating electric couplers have come into engagement with each other they are caused to slide over each other in a direction transverse to the longitudinal axes of the couplers, thus producing a polishing and cleaning 55 action and insuring a good electrical connection between each pair of co-operating contacts. In Fig. 1 of the drawings I have shown a car coupler, 26, having thereon a hook, 27, adapted to enter into a co-operating coupler and cause the two couplers to be aligned horizontally and vertically, that is transversely to their longitudinal axes. On 60 the outer side of the hook, near the base, is 55 an inclined face, 28; this inclined face being

adapted to engage with an inclined face, 29, on another coupler, the face 29 being on the opposite side of the coupler head from that on which the face 28 is located. This engagement of the inclined faces 28 and 29 70 takes place just before the coupling hooks have reached their ultimate coupled positions, causing the two hooks to be pressed toward each other and bringing about the sliding engagement between the contacts of 75 two electrical couplers which may be attached to the car couplers by suitable fastening devices, 30, passing through the ears 6 and 7 on the casing of the electrical couplers and through portions of the car couplers as, for example, through flanges, 31, cast on the car coupler heads at the proper points. Not only will the contacts of the electrical 80 couplers be brought in engagement with and wiped across each other, but the two electrical couplers will be accurately aligned and the rubber rims 25 pressed together to form a water-tight joint between them.

While I have illustrated and described with particularity only a single preferred form of my invention, I do not desire to be limited to the exact structural details thus illustrated and described; but intend to cover all forms and arrangements which come within the terms employed in the definitions of my invention constituting the appended claims.

I claim:

1. In a coupler, a casing open at the front end, a body of insulating material arranged in said casing and adapted to be taken out of and placed in the casing through said open end, contacts projecting from said body of insulating material beyond the front end of the casing, bolts passing transversely through said body and said casing to prevent displacement of said body in the longitudinal direction, and set screws arranged between one wall of the casing and said body for holding said body against movement lengthwise of the bolts.
2. In a coupler, a casing open at the front end, a body of insulating material arranged in said casing and adapted to be taken out of and placed in the same through said open end, vertical bolts extending through said casing and said body of insulating material, and adjustable pressure devices between the top of said body and the overlying wall of the casing for holding said body firmly against the bottom of the casing, and contacts carried by said body and projecting through the open front end of said casing.
3. In a coupler, a casing, a body of insulating material in said casing, the casing having an opening to permit the insertion and removal of said body of insulating material, bolts passing through said casing and through said body of insulating ma-

terial, set screws between one side of said body and the adjacent wall of the casing for exerting pressure in directions parallel to said bolts and hold said body against the 5 opposite wall of the casing, and contact pieces carried by said body and projecting beyond the casing.

4. In a coupler, a casing approximately 10 rectangular in vertical cross section and open at the front end, a rectangular body of insulating material arranged in said casing and of such dimensions as to permit it to be moved freely into and out of said open

end, bolts extending vertically through said casing and said body, set screws carried by 15 the upper wall of the casing and bearing against the top of said body so as to press said body firmly against the bottom of the casing, contact pieces slidably mounted in said body and projecting out through said 20 open end of the casing, and springs for yieldingly holding said contact pieces in their forward positions.

In testimony whereof, I sign this specification.

HERBERT E. VAN DORN.
